Primary Examiner—Catherine Tuttle(74) Attorney, Agent, or Firm—McCarter & English, LLP(57) CLAIM

The ornamental design for a combined perfume bottle and cap, as shown and described.

DESCRIPTION

FIG. 1 is a front perspective view of a combined perfume bottle and cap showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines are included for the purpose of illustrating portions of the bottle that form no part of the claimed design.
